No. 897,626.

PATENTED SEPT. 1, 1908.

W. B. KEIGHLEY.
WELT BEATING MACHINE.
APPLICATION FILED OCT. 30, 1907.

Witnesses:

UNITED STATES PATENT OFFICE.

WILLIAM B. KEIGHLEY, OF VINELAND, NEW JERSEY, ASSIGNOR TO CHARLES KEIGHLEY & SONS, A FIRM.

WELT-BEATING MACHINE.

No. 897,626.

Specification of Letters Patent.

Patented Sept. 1, 1908.

Application filed October 30, 1907. Serial No. 399,805.

To all whom it may concern:

Be it known that I, WILLIAM B. KEIGHLEY, a citizen of the United States, and residing in Vineland, New Jersey, have invented certain Improvements in Welt-Beating Machines, of which the following is a specification.

My invention belongs to the general class of shoe making machinery and has to do more particularly with a novel device for operating on welts.

One object of the invention is to provide means whereby it shall be possible to submit a welt to pressure or beating while it is being stretched or is under tension;—that is, to provide means for simultaneously stretching and pounding or beating a welt with the idea of causing such spreading of said material that it shall be capable of covering a larger surface than would otherwise be possible.

Another object of the invention is to provide a relatively simple and compact mechanical device capable of being combined with any suitable form of mechanism for beating a welt, by which it shall be possible to simultaneously beat and stretch the welt of a shoe.

These objects and other advantageous ends I attain as hereinafter set forth, reference being had to the accompanying drawings, in which,

Figure 1, is an elevation of one side of a machine made in accordance with my invention; Fig. 2, is an elevation of the opposite side of the machine shown in Fig. 1; Fig. 3, is a plan of a portion of my device; Fig. 4, is a side elevation of a modified form of my machine; Fig. 5, is an inverted plan of a form of clapper which may be used in my machine; and Fig. 6 is a side elevation of a modified form of my invention.

In the above drawings A represents the supporting frame of a machine which is provided with any form of mechanism whereby a hammer B is rapidly reciprocated in the well known manner, this hammer being carried upon one end of a rocker arm b driven from suitable mechanism such as an eccentric or crank actuated from a pulley b', and which, as its particular construction forms no part of the present invention, has not been illustrated in detail. In addition, there is also a worm fixed to the belt wheel or driving shaft b² and a worm wheel inclosed in a casing as illustrated in dotted lines in Fig. 1.

This worm wheel is fastened to a shaft, a portion of which is indicated at c, which also carries a suitably designed cam c', while a lever D, pivoted at d to the frame A of the machine, has at substantially its middle 60 point a pin d' designed to be actuated on by said cam.

The upper end of the lever D is pivoted to the end of a horizontal bar E which is free to slide in a guide box e suitably supported from the frame. The forward end of the slide bar E is turned downwardly and inwardly, as indicated in Figs. 1 and 3, so that it terminates preferably directly in the rear of the hammer B, and above and to the rear of an anvil F 70 which is rigidly fastened to the projecting portion a' of the frame so as to be immediately under the lower face of said hammer B. The anvil is held in position by a bolt a⁴ which passes through a slot in the frame as 75 indicated in dotted lines, so as to permit of said anvil being adjusted in or out as desired. The slide bar E has extending through its forward end a rod G which is provided with a thin metallic tongue so placed as to rest upon 80 the forward edge of the anvil F. Said rod G may be adjusted as to its position in the enlarged end of the slide bar E and is held in any given position by a suitable screw e'. Also mounted upon the bar G and to the 85 rear of the end of the slide bar E, is a block H held in any adjusted position on said rod by means of a set screw h, shown in Fig. 1. A pin or bolt h' extends transversely through the said block H and serves as a supporting 90 spindle or pivot for a clapper K, which in the present instance is U-shaped in form and has a substantially semicircular extension k designed to project over the anvil F and tongue g while under the hammer B. With this arrangement of parts, when the machine is in operation, the rocker arm b is caused to rapidly oscillate under the action of the eccentric or other device on the main shaft b² and the hammer is thereby caused to make a succession of rapid strokes toward and from the anvil F. At the same time the revolution of the cam c' causes the lever D to be oscillated on its fulcrum, thereby reciprocating the slide bar E and moving the tongue g and the 105 clapper K alternately forwardly and to the rear under the hammer B.

The various parts of the machine are so proportioned and timed that the hammer will usually make a number of strokes while the 110

slide bar E and its attached parts are making one complete cycle of movements to the rear and toward the front, the hammer being adjusted so that it strikes the part k of the clapper K each time it descends. If desired the parts may be so arranged that the hammer will make but one stroke for each complete cycle of movements of the clapper.

In using the device, the operator places a shoe against the front edge of the anvil F with the welt strip to be beaten in such position that it projects between the tongue and the part k of the clapper. Under these conditions the strip of welt is gripped between the said two parts owing to the blow struck upon the part k of the clapper and is pulled or stretched during the rearward movement of the sliding bar E.

Movement of the shoe is prevented because it rests against the abutment formed by the front edge of the anvil, as shown in Fig. 4, so that during the entire movement of the slide bar E the welt strip may be gripped and released several times between the tongue and the clapper, being thus not only beaten or pounded but simultaneously stretched.

Upon the forward movement of the sliding bar E, the welt strip is beaten without being stretched and is again beaten while under tension upon the next rearward movement of the tongue and clapper, and so on indefinitely. The rearward motion of the tongue and clapper while they are pressed upon by the hammer causes a stretching of the welt, and, as illustrated in Fig. 5, I may in some instances roughen the under side of the clapper so that it will better grip the welt.

Owing to the construction described and illustrated it is possible to vary not only the positions or the amount of projection of the tongue and clapper relatively to the anvil F, but also their position relatively to each other and to the hammer B, thus making it possible for the device to be used to operate upon different sizes and grades of work.

It is to be noted that the anvil serves as the means for holding the body of the shoe so that tension may be applied to the welt thereof when this latter is gripped by the tongue and clapper and moved to the rear thereby.

It is obvious that if desired, the hammer may be reciprocated in a substantially horizontal line with the tongue and clapper while the anvil remains stationary, in which case the various parts may be arranged as shown in Fig. 6. With such a construction the sliding bar E has a vertically slotted projection e⁶ into whose slot or slots extends a suitable pin or pins projecting from the vertical guide b⁶ for the hammer B. This guide is loosely connected with the end of the rocker arm b and as a consequence, said hammer, under operating conditions, is given a hori-

zontal as well as a vertical reciprocating movement.

In any of the above noted cases, either the tongue or the clapper may be omitted, though it is preferable that they be employed with the hammer and anvil as illustrated in Fig. 1.

As shown in Fig. 4, it is possible in some instances, to omit the hammer and so actuate the clapper that it shall act with the tongue to drag or stretch the welt. In the case illustrated this is accomplished by forming the clapper as indicated at K, and extending it rearwardly from its supporting pivot h² into engagement with a cam roller h⁴. The extended portion of the clapper is provided with a cam face h⁵ placed to co-act with said roller so that as said clapper is moved rearwardly by the rearward movement of the slide bar E, said cam face will engage said cam roller h⁴. As a result, its forward end is moved toward the tongue and co-acts with it to grip and stretch the welt as before. With the forward movement of the slide E, the extension of the clapper moves off of the roller h⁴ and releases the welt.

90 I claim:

1. A welt beating machine consisting of a hammer, an anvil, and means interposed between said hammer and anvil for stretching a welt while it is being beaten.

95 2. The combination in a welt beating machine of a hammer, an anvil, gripping mechanism actuated by said hammer, and means for moving said gripping mechanism from the line of action of the hammer in order to apply tension to the object engaged by said mechanism.

100 3. The combination of means for gripping a strip of welt, an abutment for preventing movement of the main portion of the shoe to which the welt is attached, means for moving said gripping means away from the shoe, and means for beating the welt while it is under tension.

110 4. A welt beating machine having means for placing a welt under tension, and means for delivering a blow or blows upon the welt while it is under tension.

115 5. The combination in a welt beating machine of a hammer, an anvil, means for operating the hammer, two structures having substantially parallel faces for gripping a welt, and means for reciprocating said structures between the hammer and anvil so that they will receive a succession of blows from said hammer.

120 6. The combination in a welt beating machine, of a hammer, an anvil, means for reciprocating the hammer, a member having a welt-engaging clapper constructed to frictionally engage the welt and projecting between the hammer and the anvil, with means for reciprocating said member to cause the

clapper to exert a stretching force on the welt under treatment.

7. The combination in a welt beating machine of a hammer, an anvil, means for reciprocating the hammer, a welt engaging clapper, a tongue placed to extend between the hammer and the anvil, and means for reciprocating said clapper.

8. The combination in a welt beating machine of a hammer, an anvil, means for operating the hammer, a tongue and a pivotally mounted clapper extending between the hammer and anvil, a bar supporting said tongue and clapper, and means for reciprocating said bar.

9. The combination in a welt beating machine of a reciprocating hammer having a co-acting anvil, a slidable bar having a tongue resting upon the anvil, a pivoted yoke on the bar having a flat projection extending between the hammer, and means for reciprocating said bar.

10. The combination in a welt beating machine of a hammer, an anvil, means operative between the hammer and anvil for gripping a welt, and placed so as to receive a succession of blows from the hammer, means for moving said gripping device alternately toward and from the anvil transversely to the line of action of the hammer, and means for operating the hammer.

11. The combination in a welt beating machine of a hammer, an anvil, means operative between the hammer and anvil for gripping a welt and placed so as to receive a succession of blows from the hammer, means for moving said gripping device alternately toward and from the anvil transversely to the line of action of the hammer, and means for operating the hammer so that it will make a plurality of strokes to one stroke of the gripping device.

12. The combination in a welt beating machine of a frame, a rocker arm thereon, a hammer having actuating means, an anvil, means for actuating the rocker arm, a cam

operated from said means, a lever mounted so as to be oscillated by said cam, a slidably mounted bar connected to the lever so as to be reciprocated thereby, a tongue rigidly mounted on said bar, and a clapper pivoted to the bar, said tongue and clapper being arranged to extend between the hammer and anvil.

13. The combination in a welt beating machine of a hammer, an anvil placed to co-act therewith, means for reciprocating the hammer, a tongue and a clapper having a supporting structure, means for moving said structure transversely to the line of action of the hammer, and means for adjusting the positions of the tongue and clapper relatively to each other.

14. The combination in a welt beating machine of a hammer, an anvil placed to co-act therewith, means for reciprocating the hammer, a tongue and a clapper having a supporting structure, means for moving said structure transversely to the line of action of the hammer, with means for adjusting the positions of the tongue and clapper relatively to each other and also relatively to the hammer and anvil.

15. The combination in a welt beating machine of a fixed abutment, means for engaging a welt, and mechanism for moving said welt engaging means alternately toward and from said abutment.

16. The combination of a fixed abutment, a clapper adjacent thereto, and means for reciprocating the clapper toward and from said abutment, said clapper being provided with a roughened surface for engaging a welt operated on.

In testimony whereof, I have signed my name to this specification, in the presence of two subscribing witnesses.
